4 Claims. (Cl. 179—170)

This invention relates to two-way telephone and like electrical signalling systems and has for its object to provide a two-way system suitable for use, for example, as the terminal equipment 5 of a two-way radio telephone system. More specifically the invention relates to two-way systems of the kind wherein a line—to be herein-after referred to as a "subscriber's line"—is associated with a transmitting thermionic amplifier and with a receiving thermionic amplifier for two-way communication, the input terminals of the transmitting amplifier being associated with the subscriber's line and the output terminals of the receiving amplifier being associated with said line through the usual hybrid coil set. As is well known, in such an installation an "ideal" hybrid coil set would be one in which the balance was so perfect that there would be no interaction between the receiving and transmitting channels 10 while the loss between either of these channels and the subscriber's line was a minimum. Accurate balance in a hybrid coil set involves that the impedance of the subscriber's line shall be accurately simulated at all frequencies employed, and 15 since, in the majority of practical cases, the subscriber's line is apt to be changed from time to time (e. g. in the case of a radio telephone service the subscriber's line in use at any time may be any of a plurality of lines leading to differentially situated subscribers) the said simulation cannot be more than approximate and therefore some out-of-balance will in practice almost always exist. For these reasons it has been customary to employ so-called "blocking devices" in 20 connection with the transmitting and receiving channels so that both channels cannot be in use at the same time. Such blocking devices, which are controlled in operation by the speech or other signal currents, may take any of a variety 25 of different forms one of the most usual arrangements being that in which normally (i. e. in the absence of speech) the transmitting channel is paralyzed (i. e. inoperative) and the receiving channel "made" (i. e. operative) speech currents 30 coming from the subscriber's line being utilized to "make" the transmitting channel and paralyze the receiving channel. Obviously, the device which paralyses the one channel and makes the other, must not operate when no speech is passing.

It is also known so to arrange matters that the operation of the blocking device is dependent, not merely upon the energy in the transmitting channel, but differentially upon this energy and 35 upon the energy in the receiving channel. Now

it will be appreciated that there will be a more or less substantial noise level in the receiving channel and this fact combined with the fact that perfect balance is in practice not obtained in the hybrid coil set, introduces a difficulty. 5 The fact that the output from the receiving amplifier is generally required to be large and the input to the transmitting amplifier may be quite small, introduces difficulty since the difference between the energy level at the input terminals 10 of the transmitting amplifier due to "noise" passed through the hybrid coil set, and the energy level at the same terminals when there is speech to be transmitted, is not very great; and, in fact, not only is the margin for operation of 15 the blocking device not very great, but the necessary adjustment for satisfactory operation is quite critical.

In the accompanying drawings, Figure 1 shows, diagrammatically, by way of example, a well known type of two-way telephone system; Figure 2 illustrates a modification of the system of Figure 1 in accordance with the principles of the present invention; Figure 3 illustrates in some detail a desirable feature of the invention; and Figure 4, which is shown in parts 4a, 4b, 4c, illustrates a practical embodiment of the invention. 20

In order that the aforementioned difficulties may be the better understood a typical well known installation will now be briefly described. 25

In this known installation which is represented schematically in the accompanying Figure 1 the subscriber's line L is associated through the usual hybrid coil set H with a transmitting channel and with a receiving channel. Included in the transmitting channel is a switch or contact device D whereby said channel may be opened or closed i. e. disconnected from or connected to the radio or other transmitter proper, while the receiving channel leads from the radio or other receiver proper may be connected through a switch or contact device E and then through the receiving amplifier G to the hybrid coil set. A blocking amplifier detector unit A is connected to receive its input from the transmitting channel at a point between the hybrid coil set H and the contact device D the output from this amplifier detector being utilized to control a blocking device C which is arranged when operated to close the contact device D in the transmitting channel and simultaneously open the contact device E in the receiving channel. The gain of this amplifier detector A is controlled in dependence upon the output from a gain controlling amplifier detector B whose 30

input is energized from a point between the input terminals of the receiving amplifier G and the contact device E in the receiving channel.

Now with this arrangement suppose that when
5 no speech is passing, the noise level at the input
terminals of the receiving amplifier G is r and that
the gain of the receiving amplifier may be ex-
pressed by a power ratio g . Suppose also that
10 the loss in energy in passing from the receiving
channel side of the hybrid coil set H through the
said set to the transmitting channel may be ex-
pressed by a power ratio h and that when speech
to be transmitted comes from the subscriber's line
15 the energy thereof may be expressed by the quant-
ity t . Now since speech from the subscriber's
line will cause equal E. M. F.'s in both the trans-
mitting and receiving channels but no E. M. F.
across the balancing network of the hybrid coil
20 set H and since, moreover, speech passing from
the receiving channel towards the subscriber's
line will cause equal E. M. F.'s across the said line
and across the balancing network when no speech
is passing, the input energy to the blocking am-
plifier detector may be expressed by $r \times g \times h$ (ig-
25 noring the "noise" from the subscriber's line).
When speech from the subscriber's line arrives
this amplifier detector will receive an energy level
 $r \times g \times h + t$. It will therefore be apparent that
30 the margin for operation of the blocking device is
small, being the amount t and that the adjust-
ment of the blocking amplifier detector A and of
the gain controlling amplifier detector B must be
very accurately made.

35 The principal object of the present invention is to render the necessary adjustments less critical and this object is achieved according to the main feature thereof by taking one of the energies which are to be differentially utilized for the control of the blocking device from the receiving 40 channel side of the hybrid coil set instead of from the transmitting channel side thereof.

In one way of carrying out the present invention the known arrangement hereinbefore described is modified as shown in the accompanying Figure 2 by connecting the input terminals of the blocking amplifier detector A to the receiving channel immediately adjacent the hybrid coil set instead of connecting these terminals to the transmitting channel adjacent the hybrid coil set.

50 Now with this arrangement, when no speech is passing, the energy level at the input terminals of the blocking amplifier detector will be $r \times g$ and, when speech from the subscriber's line arrives, the energy level at the said input terminals will be $r \times g + t$. The margin for operation is therefore still t but the necessary adjustment is less critical since it is now only necessary to adjust for a balance of the effects of $r \times g$ and t . The practical importance of this improvement will be 55 realized from the fact that when only the impedance of the subscriber's line is changed, e. g. when the hybrid coil set is changed over from one subscriber to another both the value of h is 60 changed and the value of the impedance facing 65 the output terminals of the receiving magnifier is changed, i. e. the apparent gain of the receiving amplifier is changed. These two effects are mathematically related in a manner involving the 70 simulating or balance network of the hybrid coil set, the impedance of the subscriber's line, the hybrid coils, and the impedances of the transmitting and receiving channels at the appreciate 75 hybrid coil set terminals. In practice the value of h is subject to large changes whereas the apparent change in the gain of the receiving ampli-

fier is relatively small and therefore the arrangement of the present invention provides a practical and important improvement inasmuch as the adjustments necessary for satisfactory operation are rendered substantially less critical.

A second feature of the invention is concerned with the means for differentially utilizing the two energies for control of the blocking device and, according to the said second feature, instead of employing a gain controlling amplifier detector to control the gain of the blocking amplifier detector the outputs from two correspondingly energized amplifier detectors are differentially combined and the combined energy utilized to control the blocking device. 15

One arrangement in accordance with this feature of the invention is illustrated schematically in the accompanying Figure 3. In this figure the output from an amplifier A'—whose input terminals are energized either (and preferably) 20

from the receiving channel side of the hybrid coil set (as is the device A of Figure 2) or from the other side of the hybrid coil set (as is the device A of Figure 1)—is passed through a transformer T_1 one of whose secondary terminals is connected to the grid and anode of a triode V_1 the other secondary terminal being connected through a time control circuit, consisting of a resistance R_1 and condenser C_1 in shunt, to the cathode of the triode. Similarly the output terminals of an amplifier B' whose input terminals are connected to the input terminals of the receiving amplifier are connected to the primary of a second transformer T_2 whose secondary terminals are associated with a second triode V_2 and a time control circuit C_2, R_2 in the same way as are the secondary terminals of the first transformer. The cathodes of the two triodes are connected together and connections are taken from the grid and cathode respectively of a third triode V_3 to the ends (remote from the cathodes) of the resistances R_1 and R_2 . The anode and cathode of the triode V_3 are connected together through the usual anode battery HT in series with a resistance R_3 shunting a condenser C_3 .

It will be seen that with this arrangement if the voltages passed through the two transformers T_1 , T_2 are equal the voltages across the two time control circuits C_1 , R_1 and C_2 , R_2 will be equal. The two triodes V_1 and V_2 of course act as diode rectifiers. In these circumstances, therefore, the same voltage will be applied both to the grid and to the cathode of the triode V_3 and so long as the voltages through the two transformers are the same there will be no change in the voltage across the resistance R_3 in the plate circuit of the third triode. If, however, the voltages through the transformers become different a differential action occurs and there will be a change in the voltage across the resistance R_3 .

This voltage is utilized in any convenient way (and after direct current amplification if required) to control the blocking device C_3 . Preferably the connections between the grid and cathode of third triode and the appropriate resistances 65 in the time control circuits are made, not as above stated and as shown to the ends of these resistance, but to adjustable tapping points thereon the condensers in the two time control circuits being connected between the appropriate cathodes and the appropriate tapping points. Preferably also the time constants of the two circuits which have been above described as time control circuits are much smaller 70 than the time constant which will, of course, be 75

given by the resistance-condenser combination 5 C_3 , R_3 in the plate circuit of the triode V_3 . This arrangement produces the result that when the output from the amplifier A' becomes greater than that from the amplifier B' , the voltage across the resistance R_3 is progressively reduced to zero and cannot become reversed; i. e. the voltage is limited and the time of restoration to its initial value will become independent of any 10 further increase in the excess in the output of one amplifier over that of the other so that what may be termed the "hang over" is rendered independent of the input. This desirable result would not be achieved if the time constants of 15 the circuits associated with the rectifying triodes V_1 , V_2 were high for the time of restoration in such a case would depend upon the voltage across these control circuits.

The control circuits can, if desired, be arranged 20 to be adjustable as to their time constants.

Figure 4 of the accompanying drawings, which is shown in three parts, namely 4a, 4b, and 4c, illustrates in some detail a practical embodiment 25 of the invention, said embodiment being in effect an arrangement of the type illustrated in Figure 1, but incorporating the principal feature of the arrangement shown in Figure 3.

In the arrangement of Figure 4 no actual 30 mechanical switches are employed, the switching effect of the devices D and E of Figure 1 being obtained purely electrically by rendering certain thermionic valves operative or inoperative by alteration of the grid biasses thereof.

Referring to Figure 4a a radio receiver (not 35 shown) is connected through a suitable filter illustrated within the dotted rectangle F to the input circuit of a device shown within the dotted rectangle GE (Figure 4c) this device consisting in effect of the receiving amplifier G and of the 40 switch E of Figure 1. What may be termed the "switch action" of the device GE is obtained by altering the bias fed to the two pushpull connected valves which constitute the first stage of the said device GE, this bias being altered in 45 manner to be described later by potential fed over the wire Y. When the potential fed over the wire Y is such that the two said pushpull connected valves are biased to or beyond cut-off, the effect is as though the switch E of Figure 1 50 were opened, while when the potential fed over the wire Y is such that the valves are operative to amplify, the effect is as if the switch E of Figure 1 were closed. It will be noted that the self 55 capacities of these pushpull connected valves are neutralized by neutralizing condensers NC. Neutralization substantially increases the efficiency of the "switching action" obtained. Output from the device GE is passed through an amplifier AMP (note Figure 4a) to one side of the 60 hybrid coil set H to which the subscriber's line L is connected as before. The interposition of the amplifier AMP prevents any speech currents from the line L reaching the filter F leading to the apparatus GC₁. The other side of the hybrid coil set H is connected through suitable filter F to the 65 input terminals of a device shown within the dotted rectangle DA said device constituting in effect the switch D of Figure 1 and an amplifier. The switch action of the device DA is obtained 70 in manner analogous to that in which it is obtained in the device GE by altering the bias upon the push-pull connected valves constituting the first stage of the said device DA, the bias potential for these valves being fed over the line X. The 75 output from the device DA is taken to the radio

transmitter (not shown). Energy from a point intermediate the amplifier AMP and the output terminals of the device GE is passed through a suitable filter F and a suitable variable attenuation device indicated within the rectangle GC₁ to the input terminals of the apparatus indicated at BB'.

As will be seen this apparatus consists of two single valve stages of amplification in cascade followed by a pushpull connected stage which 10 feeds through a transformer T₂' to two valves V₂' arranged to act as diodes. The valves V₂' are so connected together that they act as a full wave rectifier, the rectified output passing through a time control circuit consisting of a resistance R₂' 15 shunted by a condenser C₂'. The transformer T₂' valves V₂' resistance R₂' and condenser C₂' are analogous to the transformer T₂ valve V₂ resistance R₂ and condenser C₂ of Figure 3, the amplifier portion preceding the transformer T₂' being 20

analogous to the device B' of Figure 3. Energy from a point intermediate the hybrid coil set H and the filter F leading to the device DA, is passed through a further suitable filter F and a variable attenuation device GC₂ to the input terminals of 25

a device shown within the dotted rectangle AA', this device consisting of a single valve stage of amplification followed by a pushpull connected stage whose output is fed via the transformer T₁' to a pair of triodes V₁' arranged to operate as a 30

full wave rectifier and having a time control output circuit consisting of a resistance R₁' shunted by a condenser C₁'. The transformer T₁' valves V₁' resistance R₁' and condenser C₁' are analogous 35 to the transformer T₁ valve V₁ resistances R₁ and condenser C₁ of Figure 3 the stages of amplification within the rectangle AA' preceding the transformer T₁' being analogous to the device A'.

Tapping points upon the resistance R₁' and R₂' 40 are connected in effect to the grid and cathode 45 respectively of the first valve of a two valve arrangement shown within the rectangle CV₃ the apparatus within this rectangle being analogous to the valve V₃ of Figure 3 plus the apparatus at C (which is not shown in Fig. 3). The cathodes 50 of the valves V₁' and V₂', are all connected together and as will be obvious from Figure 4 the connections are such that differential control of the unit CV₃ is obtained from the voltages set up in the resistance R₁' and R₂'. Connection is taken from the plate of the first valve in the unit CV₃ to the effective centre point of the push-pull grid circuit of the first pushpull connected amplifier of the apparatus at GE, and, similarly, connection is taken from the plate of the second valve 55 at CV₃ to the effective centre point of the push-pull grid circuit of the first push-pull connected amplifier of the apparatus at DA.

These connections, which are indicated by the 60 references Y and X respectively, are the connections for feeding the controlling bias potentials to the devices at GE and DA respectively so as to cause these devices to give the required switch actions. The rectangle PU encloses a potentiometer unit from which steady grid and anode 65 potentials are tapped for the various valves as indicated.

The apparatus of Figure 4 includes another unit 70 not included in the schematic representations of Figures 1 and 3 said unit being indicated at Z of Figure 4b. As will be seen the unit Z receives energy from the input terminals of the variable attenuation device GC₁ inserted in the path to the input terminals of the device BB' and the said 75

device Z supplies control grid bias via the lead GB to the first valve of the apparatus at AA'. The apparatus at Z is such as to provide when actuated, an output potential sufficient to bias the first valve of the apparatus at AA' to the cut off point, the said apparatus at Z being further so designed that it is actuated by received speech level but not by received "noise" level so that when speech output comes from the device GE the device Z renders the device AA' inoperative but mere noise from the device GE will not cause the device Z to render the device AA' inoperative. The apparatus at Z forms the subject of another patent application and no claim is made in this specification to the said apparatus per se. The apparatus at Z sharply differentiates between received "noise" level and received "speech" level by reason of the fact that the "noise" level will be below the speech level and the said apparatus at Z is designed so that when the input thereto increases above a predetermined level (corresponding to the speech level to be expected) the output from the said apparatus decreases relatively sharply to a very low value. This device is preferably provided with a time control circuit whereby the time of restoration of the device may be regulated and the time of restoration should be made long to serve as a "hang-over" for weak syllables and echo effects

30 Figure 4 shows also a quantity of detail apparatus well known per se, such for example as testing jacks, meters and so forth, but it is not thought necessary to describe this apparatus in the present specification since it has nothing to do with the present invention as such.

I claim:

1. A two-way telephone or like electrical signalling system suitable for use for example as a terminal equipment in a two-way radio telephone system and comprising a normally "paralyzed" transmitting channel, a normally "made" receiving channel including a receiving amplifier, a hybrid coil set or its equivalent for associating the input terminals of the transmitting channel and 40 the output terminals of the receiving amplifier with a subscriber's line, an amplifier detector connected to receive its input at a point between said

hybrid coil set and the output terminals of said receiving amplifier, a second amplifier detector whose input terminals are energized from a point between the input terminals of the receiving amplifier and the point at which the normally "made" receiving channel may be "paralyzed", connections between said second and first mentioned amplifier detectors whereby said second mentioned amplifier detector controls the gain of the first in dependence upon the input to said second amplifier detector and a blocking device energized in dependence upon the output of the first mentioned amplifier detector for "making" the transmitting channel and "paralyzing" the receiving channel.

2. A two-way telephone or like electrical signalling system suitable for use, for example as a terminal equipment of a two-way radio telephone system and comprising a normally "paralyzed" transmitting channel, a normally "made" receiving channel including a receiving amplifier, a hybrid coil set or its equivalent for associating the input terminals of the transmitting channel and the output terminals of the receiving amplifier with a subscriber's line, an amplifier connected 20 to receive its input at a point between said hybrid coil set and the output terminals of said receiving amplifier, a second amplifier whose input terminals are energized from a point between the input terminals of the receiving amplifier and the point at which the normally "made" receiving channel may be "paralyzed", rectifiers energized from the outputs of each of said last mentioned amplifiers, a further amplifier connected 25 to be differentially controlled in dependence upon the voltage outputs from the two said rectifiers, and means for utilizing the output from said further amplifier to "make" the normally "paralyzed" transmitting channel and "paralyze" the normally "made" receiving channel.

3. A system as claimed in claim 2 in which the plate circuit of each rectifier includes a time control circuit.

4. A system as claimed in claim 2 and in which the output circuit of the further amplifier includes a time control circuit.

FRANCIS MONEY GRAHAM MURPHY.
